The ornamental design for the ultrasonic osteotome, as shown and described.

DESCRIPTION

FIG. 1 is a top, front, and left side perspective view of an ultrasonic osteotome in accordance with the present invention;

FIG. 2 is a left-side elevational view thereof, the right side elevation being a mirror image;

FIG. 3 is a top plan view thereof;

FIG. 4 is a bottom plan view thereof;

FIG. 5 is a front elevational view thereof; and,

FIG. 6 is a rear elevational view thereof.

The broken lines in FIG. 6 are included for the purpose of illustrating portions of the ultrasonic osteotome that form no part of the claimed design.
